UNITED STATES PATENT OFFICE.

HUGH LARKIN, OF ANSONIA, CONNECTICUT, ASSIGNOR TO THE ANSONIA
O. & C. COMPANY, OF SAME PLACE.

DESIGN FOR A SUSPENDER-END.

SPECIFICATION forming part of Design No. 23,500, dated July 24, 1894.

Application filed June 18, 1894. Serial No. 514,987. Term of patent 7 years.

To all whom it may concern:

Be it known that I, HUGH LARKIN, of Ansonia, in the county of New Haven and State of Connecticut, have invented a new and Improved Design for Suspender-Ends; and I do hereby declare the following, when taken in connection with the accompanying drawing, and the letters of reference marked thereon, to be a full, clear, and exact description of the same, and which said drawing constitutes part of this specification and represents a face view of a suspender-end embodying my design.

This invention relates to a design for suspender-ends and the design consists in the configuration as hereinafter described and shown in the accompanying illustration.

As herein shown, the design consists of a strap A, of inverted U-shape, terminating at

each end in a loop a. The sides of the strap A are joined by a curved strap B, which with the upper portion of the strap A form substantially a circular opening. Depending from the curved connecting strap B is a pendant C, all as shown in the accompanying illustration.

I claim—

The design for a suspender-end as herein shown and described.

In testimony whereof I have signed this specification in the presence of two subscribing witnesses.

HUGH LARKIN.

Witnesses:

FRANKLIN R. JOHNSON,
ALTON T. TERRELL.
